UNITED STATES PATENT OFFICE.

JOHN AUSTIN, OF GENEVA, OHIO.

MOUTHPIECE FOR SMOKERS' ARTICLES.

1,073,315.

Specification of Letters Patent. Patented Sept. 16, 1913.

Application filed October 4, 1912. Serial No. 723,944.

To all whom it may concern:

Be it known that I, JOHN AUSTIN, a citizen of the United States, residing at Geneva, in the county of Ashtabula and State 5 of Ohio, have invented a new and useful Mouthpiece for Smokers' Articles, of which the following is a specification.

The present invention appertains to mouthpieces for smokers' articles, such as 10 pipes, and cigar and cigarette holders.

It is the object of the present invention to provide a novel and improved mouthpiece of the character indicated which shall permit the smoke to be readily drawn there- 15 through, and which shall prevent to a great extent the smoke or the breath of the smoker from being forced back through the mouth- piece, in order to practically eliminate the accumulation of nicotin or other extraneous 20 matter within the stem or mouthpiece.

This invention also contemplates the provision of such a mouthpiece which shall not be encumbered so as to be objectionable, and which shall be simple, inexpensive, conven- 25 ient, efficient and serviceable.

This invention resides essentially in pro- 30 viding means at the inner end of the mouth- piece for continuing the duct so as to open laterally, the invention also residing in cer- tain details of construction and in the com- 35 bination of component parts as hereinafter set forth and claimed, it being understood that changes in the precise embodiment of invention herein disclosed can be made within the scope of what is claimed with- 40 out departing from the spirit of the invention.

The preferred embodiment of the invention has been illustrated in the accompany- 45 ing drawings, wherein like reference char- acters have been employed to denote corre- sponding parts, and wherein:—

Figure 1 is a perspective view of a mouth piece constructed in accordance with the 45 present invention. Fig. 2 is a longitudinal central section thereof. Fig. 3 is a sectional detail taken on the line 3—3 of Fig. 2.

Referring specifically to the drawings, the 50 numeral 10 designates the mouth piece of a pipe or cigar or cigarette holder, which is provided with the usual duct 11. This mouth piece may be constructed of the usual materials employed, such as amber, rubber, and the like, and is usually removable from 55 the stem of a pipe or the holder proper for cigars or cigarettes. The mouth piece may

also be of any suitable shape or contour, the inner end being preferably tapered.

In carrying out the present invention, a series of short longitudinal grooves 12 are 60 cut or otherwise fashioned in the periphery of the mouth piece at its inner end, and an annular baffle or ring 13 is slipped over the mouth piece and is engaged thereto at the forward ends of the grooves 12 to project 65 from the mouth piece. This ring or annulus 13 may be provided with a forwardly or outwardly projecting lip 14 around its inner edge for engaging the mouth piece, so that the ring may be better held in position. A 70 cap 15 has its edge slipped or fitted over the inner or rear end of the mouthpiece and binds upon the inner end of the mouth piece due to the taper of the mouthpiece, so that the edge of the cap is spaced from the 75 baffle 13, in order to permit the grooves 12 to open laterally and in order that the cap will be spaced from the inner or rear end of the mouth piece. Thus, the duct 11 will be continued forwardly or outwardly over 80 the rear or inner end of the mouth piece and then to open laterally at interval points around the periphery of the mouth piece. When the mouth piece is employed in con- 85 nection with a pipe or cigar or cigarette holder, it will be noted that the smoke in being drawn through the duct 11 will not pass directly into the mouth but will be di- rected forwardly through the grooves 12 and then laterally out of the forward ends 90 of the grooves, adjacent the baffle, into the hollow of the mouth. The provision of the cap will partially prevent or tend to pre- 95 vent the smoke and the breath of the smoker from being forced backwardly through the mouth piece, thus greatly eliminating the accumulation of nicotin or other foreign matter. The smoker will therefore receive the full benefit of the tobacco or weed being smoked and without any abnormal injurious 100 effect.

The cap and baffle may be stamped from suitable sheet metal or may be otherwise fashioned from various cheap or valuable metals or other materials, according to the 105 whim of the user. The said parts may be readily applied and removed from the mouthpiece for the purpose of cleansing, repair or replacement, and it will be seen that the mouthpiece may be readily and in- 110 expensively fashioned in accordance with the present invention.

In view of the foregoing, taken in connection with the drawings, the advantages and capabilities of the present invention will be apparent, it being noted that objects aimed at have been carried out satisfactorily and that the present device provides a desirable one for the purposes for which it is designed.

Having thus described the invention, what is claimed as new is:

1. A mouth piece for smokers' articles having its inner end tapered and having a series of short longitudinal grooves in its periphery at its inner end, and a cap fitting over the inner end of the mouth piece.
2. A mouth piece for smokers' articles having its inner end tapered and having a series of short longitudinal grooves in its

periphery at its inner end, a baffle ring on the mouth piece at the outer ends of the 20 grooves, and a cap fitting over the inner end of the mouth piece.

3. A mouth piece for smokers' articles having a short outer groove in its inner end, a baffle ring slipped over the mouth piece 25 and engaged thereto at the outer end of the groove to project from the mouthpiece, and a cap having its edge slipped over the inner end of the mouth piece to bind thereon.

In testimony that I claim the foregoing 30 as my own, I have hereto affixed my signature in the presence of two witnesses.

JOHN AUSTIN.
